(57) **CLAIM**

I claim the ornamental design for a food wrapper, as shown and described.

DESCRIPTION

FIG. 1 is a perspective view of a food wrapper showing my new design in an unfolded position;

FIG. 2 is a perspective view of the food wrapper illustrated in FIG. 1 in a folded position;

FIG. 3 is a perspective view of the food wrapper illustrated in FIG. 2 in a folded position;

FIG. 4 is a right side elevational view of the food wrapper illustrated in FIG. 1 in an unfolded position;

FIG. 5 is a left side elevational view of the food wrapper illustrated in FIG. 2 in a folded position;

FIG. 6 is a left side elevational view of the food wrapper illustrated in FIG. 3 in a folded position; and,

FIG. 7 is a bottom plan view of the food wrapper illustrated in FIG. 1 in an unfolded position.
